US00D579204S

(12) **United States Design Patent**
Chen

(10) **Patent No.:** **US D579,204 S**
(45) **Date of Patent:** **** Oct. 28, 2008**

(54) **TOOLBOX**

(76) Inventor: **Tsai-Ching Chen**, No. 202, Lane 330,
Sec. 7, Chang Lu Road, Fu Hsing
Shiang, Chang Hua Hsien (TW)

(**) Term: **14 Years**

(21) Appl. No.: **29/302,932**

(22) Filed: **Jan. 29, 2008**

(51) **LOC (8) Cl.** **03-01**

(52) **U.S. Cl.** **D3/315; D3/215; D3/905**

(57) **CLAIM**

The ornamental design for a toolbox, as shown and described.

DESCRIPTION

FIG. 1 is a perspective view of a toolbox showing my new design;

FIG. 2 is a front view thereof;

FIG. 3 is a rear view thereof;

FIG. 4 is a left view thereof;

FIG. 5 is a right view thereof;

FIG. 6 is a top view thereof;

FIG. 7 is a bottom view thereof;

FIG. 8 is the perspective view embodying the utilization of the toolbox; and,

FIG. 9 is the perspective view embodying the utilization of the toolbox in which the broken line is directed to environment and is for illustrative purposes only, forming no part of the claimed design.
